Thomas Hanson, Windham, Maine
Sellers Patent

It is to be agreed between the Seller's Patent and the following parts of the same containing a description of the goods of the said Thomas Hanson himself of his invention in the letter church,

With whom these goods shall come to it known that I Thomas Hanson of Windham County of Cumberland, State of Maine have invented a new and important machine for the weaving of burlap and burl, the following is a full and just description thereof. The boards of said machine being 14 inches wide these boards are placed 18 inches apart with a circular groove upon the inside of the above described boards so as to receive a bar. In the same said circular bar is confined in the groove above described by three boards placed at equal distances in the outside of each of said boards in side pieces and confined by three rods in each end of the machine passing through from bar to bar and for carrying passing through the center of the middle bar with four burlap boards attached thereto as follows within said circular groove in the end of the above described machine is attached a pinion of four inches in diameter at the end of said middle bar passes a bar with a cog wheel in one end of sixteen in diameter for the purpose of drawing into the above described pinion upon the side of said cog wheel is placed another wooden wheel of four feet ten inches in diameter near the circumference of said wooden wheel are placed four pins for the purpose of operating said machine.

What I claim as my own invention and previously known as the above described machine is the gearing that is attached and that part of said machine. A. A. said machine has a cover at the top with a hole in the center for the purpose of admitting air.
